DUCK HUNTING BOAT

Henry P. Megargee, Summit, N. J.

Application November 18, 1957, Serial No. 48,498

Term of patent 14 years

(Cl. D71—1)

Fig. 1.

Fig. 2.

Figure 1 is a side elevational view of a duck hunting boat, showing my new design, the opposite side being the same;

I claim:

The design for a duck hunting boat, as shown.
